UNITED STATES PATENT OFFICE.

CROSBY C. MCLEAN, OF PITTSBURGH, PENNSYLVANIA, ASSIGNOR TO ALLEGHENY PLATE GLASS COMPANY, OF PITTSBURGH, PENNSYLVANIA.

APPARATUS FOR DELIVERING ABRASIVE MATERIAL.

1,081,762.

Specification of Letters Patent.

Patented Dec. 16, 1913.

Application filed September 25, 1913. Serial No. 791,757.

To all whom it may concern:

Be it known that I, CROSBY C. MCLEAN, a citizen of the United States, residing at Pittsburgh, in the county of Allegheny and State of Pennsylvania, have invented certain new and useful Improvements in Apparatus for Delivering Abrasive Material, of which the following is a specification.

My invention consists of an improvement 10 in apparatus for grinding and smoothing plate glass, and refers particularly to means for classifying, supplying and collecting the abrasive material, utilizing mechanism for effecting an upward flow from the bottom 15 portions of a plurality of individual collecting wells, with supply conduits and distributing mechanism, constructed and adapted to operate in the manner more fully hereinafter set forth.

20 The apparatus comprises a preliminary well in which the overflow water from the glass grinding table is delivered, together with means for supplying fresh abrasive, a secondary well arranged to receive the overflow from the upper portion of the preliminary well, said wells being especially constructed to provide for removal of their bottom closures and each having an individual pump device, together with a surrounding dry pit within which the wells are enclosed. The said wells embody novel mechanism for effecting disturbance of the accumulation of abrasive, etc., in the bottom 25 and for facilitating the action of the pumps, and the invention embodies other features of novelty and utility in its entirety.

In the drawings illustrating one preferred installation of the apparatus,--Figure 1 is a general plan view showing the mechanism arranged with relation to the plate glass grinding machine. Fig. 2 is a transverse sectional view taken on the line II. II. of Fig. 1. Figs. 3 and 4 are vertical sectional views, enlarged, of the classifying hopper which receives the abrasive from the secondary well and delivers it to the table. Fig. 5 is an enlarged vertical sectional view of one of the settling wells and its pump. Fig. 6 is a plan view showing the piping arrangement for the disturbing fluid supplied to the bottom of said well. Fig. 7 is a vertical sectional view of the lower portion of the well at right angles to Fig. 5. Fig. 8 is a cross sectional view, taken on the line VIII. VIII. of Fig. 5.

Fig. 9 is an enlarged sectional detail view showing the construction of the bottom of the well and its opening door.

In the drawings, 2 represents the rotating table of a plate glass grinding and polishing machine of usual, well-known construction which is provided with the customary grinding runners and driving mechanism, not shown. At a suitable distance above the table and runners are preferably provided 60 convenient delivery troughs or conduits 3, 4, one of which is adapted to receive the abrasive from one of the wells and the other to receive the abrasive from the other well, under the control mechanism hereinafter 70 described, and to deliver it through the opposite spout terminals of the troughs to the table as needed. The table 2 is surrounded by an annular collecting trough or ditch 5 within an outer protecting wall 6, the ditch 75 being inclined toward an outlet opening or conduit 7 and provided with a protecting screen 8 for separating any coarse or foreign matter, allowing the finer particles to pass downwardly into the circulation.

Laterally off-set from the apparatus above described, but in convenient juxtaposition thereto, is a dry well 9 of concrete or other suitable material, sufficiently large to provide for the installation of the preliminary 85 and secondary wells 10 and 11 and of the entrance to the bottom of the pit of one or more workmen, ample space being provided for such purpose. The bottom of the well is preferably tapered toward a lowermost 90 sink hole 9' from which any collected water may be removed by pumping.

A conduit 12 leads from the cavity 7 below the screen 8 into the preliminary well 10, said conduit having a fitting 13 to which by 95 a conduit 14 the fresh sand hopper 15 is connected, whereby fresh sand may be supplied from time to time by gravity, as needed.

While the preliminary well 10 and the 100 secondary well 11 are of substantially the same construction, I prefer that the bottom of the preliminary well shall be located some distance above the secondary well, as shown, and these wells are connected at a 105 point near their upper ends by an overflow conduit 16 by which the secondary well is supplied from the preliminary, and the finer unused particles of abrasive are carried over into it. The secondary well is also 110

provided at a slightly higher level with an overflow conduit 17, through which surplus water, fine unused material, slime, etc., are carried off to the sewer.

- 6 Each of the wells is provided with an air lift or pump device 18 of a construction adapted to effect an upward flow of the water and abrasive from the bottom portion of the well. As shown, the pump consists 10 of a cylindrical body portion having an air conduit 19 which may be conveniently made of a pipe having a jet terminal 20 turned upwardly into its interior above its lower end. The air supply pipe 19 leads upwardly through the well 10 and is provided 15 with a controlling valve 21 and is connected with a main air supply pipe 22 leading from any suitable source of pressure. The secondary well 11 is likewise provided with the same construction of pump and air supply 20 having a controlling valve 21' and adapted to operate generally in the same manner, but located at a somewhat lower level than the pump just described, within the bottom portion of the secondary well 11. Each of 25 the wells 10 and 11 is provided with a removable bottom 23 hinged at 24 to a terminal surrounding ring 25, to which the bottom is fixedly secured by a series of bolts 30 26 easily inserted and removed through lateral slots 27 in the bottom and ring, thus facilitating easy and quick connection or disconnection. The bottoms 23 may be provided, as shown, with centrally arranged 35 hollow lugs 28 forming circulating connections and adapted to provide for outward flow of the contents of the well through a controlling valve 29 having a stem 29' extending laterally therefrom. By this means 40 the well may be drained into the surrounding pit before opening the hinged bottom 23.
- For the purpose of agitating or dislodging the accumulated material in the bottom of each well, I provide a series of water supply pipes 30 connected at the upper end of each well with headers 31 and 32 respectively, each header having a controlling valve 33, and being connected with a common supply pipe 34. The pipes 30 are in 50 pairs, as shown, two pipes for each header, which pass downwardly around the outside of the shell 10 or 11 of each well, and are inserted inwardly through the shell and connected by suitable fittings. One of the 55 said pipes is turned upwardly at an angle of, say 45° , as shown at 35, and the other turned downwardly in the same manner, as indicated at 36, so that the inner terminals of each pair alternate in direction, up and 60 down. The four terminals of the two pairs of pipes, being thus alternately arranged, are capable of supplying streams of water of any desired volume or force, either through one pair or both, as controlled by 65 valves 33, for the purpose of effectually

starting or loosening the accumulated material and facilitating its entrance into the bottom of the air lift or pump, through which it is then carried upwardly.

Pump 18 of the preliminary well 10 is 70 provided with a supply pipe 37 which leads over to one of the distributing troughs 4, by which the coarse abrasive is supplied to the table for the initial operations, pipe 37 having a controlling valve 38 and a downwardly directed return pipe 39 having a valve 40, connected behind valve 38 and adapted to return the material to the circulation when it is not required for the table. It will be understood that the flow of the 80 coarse abrasive through pipe 37 may be accurately controlled by valve 38 and that the location and slope of the pipe is such as to utilize gravity to assist in its travel. The secondary well 11 is likewise provided 85 with a similar pipe 41 leading upwardly from the well to a higher level where it discharges into a classifying tank 42. This tank, which is of well-known construction, is preferably provided with tapering walls 90 43 at its sides and ends and an adjustable gate 44 which may be set at any desired distance above one of the inclined walls for the purpose of controlling the flow downwardly 95 toward the bottom.

The classifier 42 is provided with a series of outlet terminals 45 at the lower portions of which separate conduits 46 are swiveled and lead off to the distributing trough 3, by which the abrasive is distributed to the 100 grinding table for finishing. These conduits 46 may also discharge directly to the grinding table direct if preferred. In the construction of the classifier, means are provided for effecting operation of any particular one of the conduits 46 by controlling the outlet from terminals 45 through individual valves 47 adapted to admit flow-controlling streams from a supply pipe 48, thereby operating to set up a supply of water and abrasive through connection 45 to its supply pipe 46. The classifier, as to these features however, does not itself form any essential part of the present invention, and may be substituted by any other 110 equivalent mechanism for effecting distribution of the classified abrasive as needed in the successive steps of the finishing operation.

The apparatus will be readily understood 120 from the foregoing description. At the commencement of the operation, coarse material, as sand, is supplied to the table from the preliminary well 10 by its pump and connections, the overflow from the table 125 with the used abrasive and carrying any additional supply of fresh abrasive from hopper 15, together with any necessary additional water from pipe *a*, passing backwardly into the preliminary well and into 130

the circulation, the operation being carried on until the coarse grinding of the glass is accomplished. Overflow from the preliminary well through conduit 16 carries 5 water and finer abrasive in suspension into the secondary well 11, and surplus water or useless material as very fine sand or "float," which is not coarse enough to be used as an abrasive, falling off through the 10 conduit 17 to the sewer. The finer abrasive in the secondary well is carried by the operation of its air lift pump and pipe 41 into the classifier 42, being delivered therefrom, as described, in successively finer 15 grades for the finishing operations. By this means a very large supply of sand and water may be fed to the table through the double spout 4 for facing. If preferred however, the pipe 41 may be led directly to the 20 table and the abrasive discharged thereon without passing it through the classifier 42. After the grinding operation with the coarser abrasive is finished, valve 38 may be closed and valve 40 opened, if the pump in 25 well 10 is continued, whereupon the coarser abrasive will merely circulate back through the screen 8 and conduits 7 and 12 to the well without being supplied to the table.

The pump in the preliminary well may be 30 discontinued, if desired, in which case the coarse abrasive may be accumulated in the bottom of the well. At any time it is required it may be readily loosened by the jet pipes 35, 36, such operation being easily 35 controlled and regulated for one or both wells, as desired, so that the apparatus is in no way interfered with by the settling of the abrasive to the bottom, and the operation in no way depends upon the maintenance of 40 the abrasive at any predetermined level. The coarse sand may, however, be maintained in suspension and circulation by continuing the operation of the pump, as may also be done with the finer sand in the sec- 45 ondary well, if desired.

The several conduits 46 are so arranged that they may be successively diverted in a lateral direction to the annular ditch, as indicated at 46', Fig. 1, by merely swinging 50 them around upon their connections, thereby enabling the operator to use the finishing sand of one grade and each grade successively, by successively diverting the second and third conduit 46 in the same manner, 55 and so on until the four grades of sand have been applied, after which both of the air lift pumps are shut off by their controlling air valves. The agitating jets in the bottom of each well may be then opened to their capacity by the controlling valves, preventing 60 the settling of sand in the bottom of the wells, the operation being easily and accurately controlled, as desired.

The operator is thus enabled to accurately 65 regulate the quality and rate of flow of the

abrasive to the grinding table according to the work being done, while the provision for the return of all of the abrasive by gravity to the circulation avoids any loss, effecting a maximum of efficiency and economy.

The advantages of the invention will be appreciated by all those familiar with this class of apparatus. It may be changed or varied by the skilled mechanic in different features of detail, proportions, or design, 70 but all such changes are to be considered as within the scope of the following claims:

What I claim is:

1. In glass grinding apparatus, the combination with a glass grinding table, of a 80 surrounding collecting trough leading to a discharge conduit, a collecting well connected therewith, an air lift device within the well having a delivery conduit leading to the grinding table, and means for disturbing the material at the bottom of the well, substantially as set forth.

2. In glass grinding apparatus, the combination with a glass grinding table, of a 90 surrounding collecting trough leading to a discharge conduit, a collecting well connected therewith, an air lift device within the well, a distributing hopper, a conduit leading from the air lift device to the hopper, means for distributing the abrasive from 95 the hopper to the table, means for draining the collecting well, and means for collecting the drained contents thereof, substantially as set forth.

3. In glass grinding apparatus, the combination with a glass grinding table, of a 100 surrounding collecting trough leading to a discharge conduit, a collecting well connected therewith, an air lift device within the well for delivering the abrasive and water 105 to the table, and a closure removably secured to the bottom of the well, substantially as set forth.

4. In glass grinding apparatus, the combination with a glass grinding table, of a 110 surrounding collecting trough leading to a discharge conduit, a collecting well connected therewith, an air lift device within the well for delivering the abrasive and water 115 to the table, a supplemental outer surrounding well extending below the bottom of said well, and means for opening and closing the bottom of said first named well for discharging its contents into said surrounding well, substantially as set forth.

5. In glass grinding apparatus, the combination with a glass grinding table, of a 120 surrounding collecting trough leading to a discharge conduit, a collecting well connected therewith, an air lift device within the well, means for draining the contents of the well, and a surrounding dry pit inclosure for the well, substantially as set forth.

6. The combination with a grinding ma- 125 chine, of a well for collecting water and 130

abrasive, means conducting the overflow from the table to said well, means for supplying abrasive and water from within the well to the table, means for furnishing fresh abrasive to the well, and variously directed disturbing water jet devices at the bottom of the well, substantially as set forth.

7. The combination with a grinding machine, of a well for collecting water and abrasive, means conducting the overflow from the table to said well, means for supplying abrasive and water from within the well to the table, a second similar well connected with said well by an overflow conduit and having similar means for supplying abrasive and water to the table, and means for disturbing the accumulated abrasive in the bottoms of said wells, substantially as set forth.

20 8. The combination with a grinding machine and its overflow conduit, of a collecting well having a removable bottom provided with a drain cock, means connecting the overflow conduit with said well, a sur-

rounding dry pit, an air lift device within 25 the well having a pipe leading to the grinding machine, and a series of disturbing jet pipes leading to the bottom of the well, substantially as set forth.

9. The combination with a grinding machine and its overflow conduit, of a collecting well having a removable bottom provided with a drain cock, means connecting the overflow conduit with said well, a surrounding dry pit, an air lift device within 35 the well having a valve controlled pipe leading to the grinding machine, a valve controlled branch pipe leading to the overflow conduit, and means for disturbing the abrasive in the bottom of the well, substantially 40 as set forth.

In testimony whereof I hereunto affix my signature in the presence of two witnesses.

CROSBY C. McLEAN.
